UNITED STATES PATENT OFFICE.

CLARENCE B. HODGES AND CHARLES H. HODGES, OF DETROIT, MICHIGAN,
ASSIGNORS OF ONE-HALF TO HENRY C. HODGES AND CHARLES C.
HODGES, BOTH OF SAME PLACE.

LUBRICATOR FOR LOCOMOTIVES.

SPECIFICATION forming part of Letters Patent No. 291,847, dated January 8, 1884.

Application filed November 7, 1883. (No model.)

To all whom it may concern:

Be it known that we, CLARENCE B. HODGES and CHARLES H. HODGES, of Detroit, county of Wayne, State of Michigan, have invented 5 a new and useful Improvement in Lubricators for Locomotives; and we do declare the following to be a full, clear, and exact description of the same, such as will enable others skilled in the art to which it pertains to make 10 and use it, reference being had to the accompanying drawings, which form a part of this specification.

Our invention consists of the combination 15 of devices and appliances hereinafter specified, and more particularly pointed out in the claims.

In the drawings, Figure 1 is a side elevation of a locomotive, illustrating our said invention. Fig. 2 is a front elevation of the same. 20 Fig. 3 represents a variation. Fig. 4 is another variation.

This invention is designed to overcome a difficulty very common with locomotive-lubricators. That difficulty arises as follows: Lubricators have usually their condensers connected directly with the steam-space of the boiler. The oil-exit is then led off to the steam-chest or to the dry-pipe. In either event the interior of the lubricator is in equilibrium so long as the engine is running, during which period it receives a back pressure from the dry-pipe or steam-chest, to counteract the direct pressure of steam from the boiler through the condenser. When steam is cut off, however, from the dry-pipe—as, for instance, when the engine is at rest, or when going down grade, or when slowing up at a station—its equilibrium is destroyed, leaving only the direct pressure from the boiler, which 30 blows out and wastes a considerable quantity of oil. Our invention overcomes the difficulty, and the following is a description of the same:

A is a locomotive-boiler; B, its steam-dome. C is its cylinder; D, the ordinary "tallow-pipes," so called, by which tallow or lubricating material is conducted to the steam-chest.

d represents stop-cocks for preventing steam from blowing back out of the tallow-cups.

E represents the body of our lubricator; E', 50 its condenser.

F is a pipe connecting the condenser with

the steam-space of the boiler either through the steam-table F', as shown in Fig. 1, or by passing directly through the boiler-shell.

G is the usual sight-feed, in which oil rises 55 in visible drops through the water contained in the glass tubes, the feed being regulated in the usual manner by globe valves or stop-cocks H.

I is the oil-exit pipe, and I' a valve for throttling the passage, and so steadyng the feed.

J represents a pipe connecting the steam-pipe F with the top of the visible feed-chamber.

The operation of the device will now be understood. The engineer removes the usual valve located at K at the steam-chest. The lubricator operates in the usual manner so long as steam is on the cylinder, maintaining the equilibrium within the lubricator. When 70 steam is shut off, the equilibrium within the lubricator is still maintained through the connection J, which serves to exert substantially the same back pressure down through the visible feed-chamber G to counteract the direct 75 pressure of steam from the condenser. This construction utilizes the tallow-pipes which are found upon most locomotives and convey the oil directly to the valves within the steam-chest. We do not, however, limit ourselves 80 to a construction which employs the tallow-pipes, for, as shown in Fig. 3, we may connect the oil-outlet directly with the dry-pipe. We would also have it understood that we do not limit ourselves to a construction in which the 85 steam-pipe F is connected with the top of the visible feed-chamber, for, as shown in Fig. 4, we propose to connect the top of the condenser-chamber directly with the top of the visible feed-chamber. This latter construction makes 90 the connection J a part of the lubricator itself and not a part of its boiler-connections. This construction accomplishes a valuable purpose in connection with a visible feed-chamber. It causes the drops which indicate the rate of 95 feed to move with the same regularity, or nearly so, at all times, and avoids the usual spirt of oil at the instant of shutting off steam which has heretofore served to displace the water in the chamber and to fill it with oil.

Instead of using the valve in the oil-exit pipe for throttling the oil, we generally reduce the

orifice in the oil-exit pipe at a point between the top of the feed-chamber and the said valve. We, in fact, usually employ both the valve and the reduced orifice, as shown in Fig. 4 by 5 dotted lines.

Where this device is applied to a sight-feed lubricator it is not absolutely essential, though preferable, that the pipe J should enter at the top of the feed-chamber; but it may enter at 10 any point on the oil-exit pipe.

What we claim is—

1. In a locomotive-lubricator, the combination, with the visible feed-chamber G and the condensing-chamber E', of an exterior steam-pipe connection between the upper portion of 15 the condenser, the top of the visible feed-chamber, and the steam-space of the locomotive-boiler, substantially as described.

2. The combination, with a locomotive, of 20 a lubricator having a steam-inlet pipe connected with the steam-space of the boiler, an oil-exit pipe leading from the top of the visible feed-chamber into the tallow-pipes, and a steam-conduit connecting the top of the visible 25 feed chamber with the steam-inlet pipe or steam-space above the water-level of the condenser, substantially as described.

3. A lubricator combining the following elements: first, an oil-reservoir, a condenser, steam-inlet pipe, a visible feed-chamber, in which the oil rises through the water, a conduit connecting the top of this chamber with the steam-inlet or steam-space above the water-level of the condenser, an oil-exit pipe leading from the top of the feed-chamber, and a throttling-valve located in the said oil-exit pipe, substantially as described.

4. In a locomotive-lubricator, the combination, with the condenser E' and visible feed-chamber G, of an exterior steam-pipe connection between the upper end of the visible feed-chamber and the steam-space of the boiler, and a connection between the upper part of the condenser and the said steam-pipe connection, substantially as described.

In testimony whereof we sign this specification in the presence of two witnesses.

CLARENCE B. HODGES.
CHARLES H. HODGES.
